WRENCH

Filed Nov. 26, 1928

UNITED STATES PATENT OFFICE

CHARLES B. GARTRELL, OF KANSAS CITY, MISSOURI

WRENCH

Application filed November 26, 1928. Serial No. 322,040.

My invention relates to wrenches of the quick adjustable type and one object is to provide a wrench of this character whereby the finest adjustment of the jaws can be had for the purpose of firmly gripping nuts or other articles of different sizes.

Another object is the provision of a wrench having a rotatable nut which can be thrown in mesh with a threaded portion of the wrench for the purpose of adjusting the jaws in the usual way, or can be thrown out of mesh with said threaded portion to permit quick adjustment of the jaws.

A further object of the invention is the provision of a wrench which consists of but few parts and is of simple, durable construction and well adapted to withstand the strains to which tools of this character are ordinarily subjected.

In order that the invention may be fully understood, reference will now be had to the accompanying drawing, in which:

Fig. 1 is a side elevation of a wrench made in accordance with the invention and with the rotatable nut intermeshing with the threaded portion of the wrench so that the jaws may be adjusted in the usual way.

Fig. 2 is a broken side elevation of the wrench with the rotatable nut thrown out of engagement with the threaded portion of the wrench so that the jaws can be quickly adjusted towards or away from each other.

Figs. 3 and 4 are cross sections on lines 3—3 and 4—4 of Figs. 1 and 2, respectively.

Fig. 5 is a detail perspective view of the rotary nut and a member in which it is mounted.

Fig. 6 is a broken side elevation of a modified form of wrench made in accordance with the invention.

Referring in detail to the different parts, 2 designates a shank provided at one end with a handle 4 and at its other end with a fixed jaw 6.

8 designates a housing having a hollow portion 9 through which the shank 2 freely extends. Said housing 8 is provided with a jaw 10 which can be moved back and forth on the shank 2 with the housing 8 and has an open-

ing 12 for a purpose which will hereinafter appear.

14 designates a member carrying a rotatable nut 16 adapted to intermesh with the threaded portion 18 of the shank 2 and adjust the housing 8 with its jaw 10 towards or away from the fixed jaw 6. The nut 16 has continuous threads 15 intermeshing with the threads 18 and is mounted upon a shaft 17 carried by the member 14.

The nut carrying member 14 is mounted upon a pivot 20 extending through the opening 12 and supported by the housing 8. The nut carrying member 14 is preferably of U-shaped form and has two resilient arms 22 adapted to frictionally engage the adjacent sides of the opening 12 and hold said member 14 in the position shown by Figs. 1 and 3.

The movement of the nut carrying member 14 in one direction is limited by lugs 24 projecting from the arms 22 and adapted to contact the sides of the opening 12, Figs. 1 and 3, while the movement of said nut carrying member 14 in the opposite direction is limited by its corner 26 contacting the adjacent end of the opening 12, Figs. 2 and 4.

When the jaws 6 and 10 are to be adjusted in the ordinary way the nut 16 is left in mesh with the threads 18 as shown by Figs. 1 and 3, but when quick adjustment of said jaws is desired the nut 16 is swung bodily out of engagement with the threads 18 to the position disclosed by Figs. 2 and 4. If after making a quick adjustment of the jaws to grip a nut or other article it is found that the nut 16 cannot be swung back into mesh with the threads 18 on account of contacting the sides of the latter, the housing 8 may be moved back a short distance to permit the threads 15 to properly intermesh with the threads 18, after which the jaws may be adjusted to firmly grip and hold the article by rotating the nut 16 in the proper direction.

In the modified form disclosed by Fig. 6 the construction and operation of the parts is similar to that of the parts disclosed by Figs. 1 to 4, inclusive, as is evidenced by corresponding reference numerals with exponents "a", the main difference being that the movable jaw 10^a is fixed to the threaded shank 2^a.

while the nut 16^a is rotated only to effect adjustment of the jaw 10^a and does not move longitudinally with said jaw.

From the foregoing description it is apparent that I have provided a wrench embodying the advantages above pointed out, and while I have shown two forms of said wrench I reserve all rights to such other forms and modifications as properly fall within the spirit and scope of the invention as claimed.

Having thus described my invention, what I claim and desire to secure by Letters Patent, is:

1. A wrench consisting of a threaded portion having a fixed jaw at one end and a handle at its opposite end, a housing slidably mounted upon the threaded portion of the wrench and provided with a jaw and an opening, a nut having external threads for engagement with the threaded portion of the wrench, a shaft extending axially through said nut, a U-shaped member carrying said shaft and operably mounted in the opening in the housing so that it may carry said nut in and out of engagement with the threaded portion of the wrench, said U-shaped member having two resilient arms for frictionally engaging the adjacent sides of the housing opening to hold the nut in engagement with the threaded portion of the wrench, and a member projecting from one of said arms for engaging the housing and checking the movement of the U-shaped member after the same has been adjusted to carry the nut into engagement with the threaded portion of the wrench.

2. A wrench consisting of a threaded portion having a fixed jaw at one end and a handle at its opposite end, a housing slidably mounted upon the threaded portion of the wrench and provided with a jaw and an opening, a nut having external threads for engagement with the threaded portion of the wrench, a shaft extending axially through said nut, a U-shaped member carrying said shaft and operably mounted in the opening in the housing so that it may carry said nut in and out of engagement with the threaded portion of the wrench, said U-shaped member having a corner for engaging the adjacent end of the opening and thereby limiting the movement of the U-shaped member when the same is adjusted to carry the nut out of engagement with the threaded portion of the wrench, and means projecting from the U-shaped member for engaging the housing and checking the movement of said U-shaped member when the latter is adjusted to carry the nut into engagement with the threaded portion of the wrench.

In testimony whereof I affix my signature.
CHARLES B. GARTRELL.
